UNITED STATES PATENT OFFICE.

ANDREW T. MOATS, OF PLEASANTVILLE, IOWA, ASSIGNOR TO THE BLACK DIAMOND MINING TOOL COMPANY, OF SAME PLACE.

MINER'S GRIP OR BRACKET FOR SUPPORTING COAL-DRILLING MACHINES.

SPECIFICATION forming part of Letters Patent No. 412,522, dated October 8, 1889.

Application filed June 24, 1889. Serial No. 315,303. (No model.)

To all whom it may concern:

Be it known that I, ANDREW T. MOATS, a citizen of the United States, residing at Pleasantville, in the county of Marion and

5 State of Iowa, have invented a Miner's Grip-Bracket for Supporting a Drill, of which the following is a specification.

My object is to provide a device that can be readily fastened to the wall in a drift and 10 braced to project horizontally in such a manner that it will support a drill, and also readily detached and folded to facilitate moving it from one point in the mine to another.

15 My invention consists in the construction and combination of a straight bar having a hook at one end and an eye at the other, a screw, and an internally-screw-threaded tube, and a drill-rest, as hereinafter set forth, 20 pointed out in my claim, and illustrated in the accompanying drawings, in which—

Figure 1 shows the device in position in a mine as required for practical use. Fig. 2 shows it folded, as required, to facilitate 25 handling and economizing space in packing, storing, and shipping. Fig. 3 is a perspective view of the hook on one end of the bracket, and Fig. 4 is an edge view of the drill-rest on the other end.

30 A is a straight bar of T-iron.

B is an integral hook on one end of the bar projecting downward at right angles. The opposite end has the flange on its under side and center removed or flattened. A 35 perforation formed in the end admits a drill-rest C to be detachably connected by means of a screw-bolt, so that it can be rotated to direct a drill placed thereon at angle desired.

40 D is a screw hinged to the flange of the bar A, that extends into an internally-screw-threaded tube H. The free end of the tube is pointed and adapted to penetrate the wall of a drift, as shown in Fig. 1.

45 J is a handle extended through a transverse bore in the tube in such a manner that the handle can slide longitudinally to facilitate rotating the tube therewith.

In place of hinging the screw to the bar A, the tube may be hinged thereto and the screw 50 placed therein and provided with a handle for rotating it.

To fasten and brace the complete device in a drift, I make an opening in the wall adapted to admit the hook B, as shown in 55 Fig. 1, and then place the pointed end of the tube against the wall and rotate the tube by means of the handle. The brace composed of the tube and screw is thus lengthened and the bar A pressed upward, as required, to 60 clamp the hook fast. If the form of the opening in which the hook is inserted require a wedge to be placed on top of the hook, the wedge can be readily applied, as shown in 65 Fig. 1, so that there will be resistance to the upward movement of the bar A sufficient to force the lower end of the brace into the wall to firmly fasten and brace the complete device as required to support and operate a drill thereon.

70 To detach the device, rotate the tube in a reverse way to relax the pressure of the brace and then withdraw the hook from the hole in the wall.

I am aware adjustable braces have been 75 combined with drill-supports adapted to be fastened to a wall; but my manner of constructing and combining an extensible brace with a straight bar and drill support so that it can be folded flat upon the bar when not 80 in use to facilitate handling and shipping, and readily adjusted to brace and support the bar in a horizontal position, and also to aid in clamping the bar fast to a wall, is novel and greatly advantageous, in that the brace 85 can be readily lengthened and shortened, and its pointed free end inserted in the same perpendicular face of the wall in which the hook on the end of the bar is inserted, to rigidly fasten the bar and support it at any 90 point of elevation and at any angle desired by simply rotating the sleeve H after the bar and brace are connected with the perpendicular wall, as illustrated in Fig. 1.

I claim as my invention—

An improved miner's adjustable bracket

and drill-support comprising a straight bar having a hook at one end adapted to be fixed in a perpendicular wall, and a swiveled drill-support at the other end, a screw-threaded bar hinged to the straight bar near the drill-support, a screw-threaded sleeve fitted to the hinged bar, and means for ro-

tating the sleeve on the hinged bar, in the manner set forth, for the purposes stated.

ANDREW T. MOATS.
